ADVERTISING DISPLAY DEVICE

Edward F. Hall and Arnold J. Lageson, Minneapolis, Minn.; said Lageson assignor of one-fourth to Howard O. Williams, Minneapolis, Minn.

Application December 16, 1946, Serial No. 716,554

3 Claims. (Cl. 40—125)

1

Our invention is related to an advertising display device which is constructed to attract the attention of a casual observer. In particular it is related to a device in which a liquid column is circulated through a transparent medium, and a small quantity of gas is introduced into the moving liquid column in the form of bubbles in a manner to attract attention. To further lend attraction to the device a luminescent background may be provided for the transparent medium, to emphasize the visual effect of the moving column of liquid and bubbles.

An object of our invention is to provide a display device in which gaseous bubbles or voids are periodically introduced into a liquid which is circulated through a transparent medium or system of tubes formed to outline the advertising matter to be displayed.

A further object is to provide an illuminated display device in which gaseous bubbles or voids, preferably of air, are periodically introduced into a moving liquid column that is being circulated through a transparent medium.

Other and further objects will become apparent from the following description and claims, and in the applicants' drawing in which:

Fig. 1 is a front elevation of an advertising device in which the invention is incorporated;

Fig. 2 is a front elevation partly in cross-section taken from the rear of Fig. 1;

Fig. 3 is an enlarged side elevation taken on the lines 3—3 of Fig. 2;

Fig. 4 is a detailed view of a transparent tubular conduit having a moving column of liquid and bubbles passing therethrough; and

Fig. 5 is a sectional top elevation taken on the lines 5—5 of Fig. 2.

Referring now to the drawing and particularly to Fig. 1, reference numeral 10 indicates a container upon the top of which is supported a screen 11 by means of brackets 12 and 13. Screen 11 is shown as being formed of glass or the like, but may be of any particular material, and, if desired, may be coated with a luminescent substance. Extending upwardly from container 10 is a continuous transparent tubular conduit 14 which has been formed into the shape of the desired advertising subject matter. Also mounted on screen 11 is an illuminating medium which may take the form of a luminescent neon tube 15. As shown tube 15 extends adjacent the periphery of screen 11, but if desired it may be formed to take the shape of conduit 14, as shown in Fig. 4, and serve as a background therefor to directly illuminate conduit 14.

Referring now to Fig. 2, which is a view taken from the rear of Fig. 1, within container 10 is shown a chamber 15 which is open at the top and which is adapted to receive a quantity of liquid 16 that may be introduced through funnel 17. The return end 14b of conduit 14 extends into chamber 15. There is also provided an outlet drain 18 for removing liquid 16 from chamber 15 for cleansing purposes.

Also located in container 10 adjacent chamber 15 is another liquid chamber 20. Inter-connecting chambers 15 and 20 is a conduit 21 which carries a valve 22 for controlling the flow of liquid 16 between chambers 15 and 20 in such a manner as to accurately control the liquid level in chamber 20. When the device is not in operation or at the beginning of operation, if the valve is open to any degree, the level in the two chambers will equalize. If desired also, the valve 22 may be left closed when the device is out of operation. Located above chamber 20 is an electric motor 23 which is provided to drive a suitable liquid circulating means, shown in the form of centrifugal pump 24, by means of a driveshaft 25. A pair of supporting members 26 interconnect motor 23 and pump 24 to rigidly support these members with relation to each other. As best shown in Fig. 5, pump 24 is provided with a central bearing 27 around which is an annular inlet 28. Pump 24 is also provided with a peripheral outlet 29 which is joined to the inlet end 14a of conduit 14.

In order to electrically operate neon tube 15 and motor 23 electric connections are provided which are adapted to be joined to a conventional source of current. A conventional plug 30 provided with a pair of conductors 31 and 32, one of which is provided with a movable switch 33 to control the flow of current through conductors 34 and 35 to motor 23 and to the primary side of a transformer 36. From the secondary side of transformer 36 a pair of conductors 37 and 38 extend to the opposite ends of neon tube 15 to convey high voltage current through the rarified gases in tube 15.

In operation, the advertising display device functions in the following manner. A quantity of liquid 16 which may be water or any other liquid substance, is introduced into chamber 15 through funnel 17 until a substantial quantity is present therein. During the filling operation valve 22 is closed so as to exclude liquid from chamber 20. Plug 30 is inserted in a source of electricity such as A. C. current and when switch 33 is moved to a closed position motor 23 is ener-

gized by a circuit which may be traced as follows: from plug 30, through conductor 31, conductor 34, conductor 35, conductor 32 through switch 33 back to plug 30. This causes motor 23 and pump 24 to commence operation and initially it will only circulate air through conduit 14. After pump 24 has been started, valve 22 is opened to allow liquid 16 to pass from chamber 15 to chamber 20 until the liquid level in chamber 20 is slightly above the inlet opening 28 of pump 24 which causes pump 24 to circulate liquid through conduit 14. After conduit 14 has been filled with liquid, valve 22 is thereafter throttled to the point where pump 24 draws in through its inlet 28 a major proportion of water and a minor proportion of air from chamber 20. The introduction of air through opening 28 of pump 24 causes voids or bubbles 40 to be formed in the liquid which passes through conduit 14, and the size or spaced regularity of the voids or bubbles 40 may thereafter be controlled by controlling the opening of valve 22 to alter the proportions of water and air.

Coincident with the starting of motor 23, as previously mentioned, a circuit is completed from the secondary side of transformer 36 through conductors 37 and 38 to neon tube 18, so that tube 18 becomes luminescent at the same time that motor 23 is energized and the luminescence of the tube tends to make the moving column of liquid and bubbles through conduit 14 more striking and attractive to the eyes of a casual observer. The appearance of this moving column of liquid and bubbles will take the form shown in Fig. 4 of the drawing although the size of bubbles 40 may be changed by regulation of valve 22 in such a manner as to increase or decrease the quantity of water admitted to chamber 20, since an increase in liquid level in chamber 20 decreases the size of bubbles 40 and vice versa.

It will be apparent to those skilled in the art that our invention may take any one of a number of forms and therefore we do not wish to be restricted to the single illustration but rather only to the extent of the appended claims.

We claim:

1. An advertising display device, comprising a chamber, a source of gas communicating with said chamber, a liquid pump having an inlet and an outlet, the inlet of said pump being positioned within said chamber and extending upwardly from the lower surface thereof, a transparent conduit connected at one end to the pump outlet, a source of liquid, and valve means positioned between said source of liquid and said chamber for controlling the flow of liquid into said chamber in such a manner that the liquid

level in said chamber is maintained slightly above the level of the inlet to the pump whereby the suction of the pump causes a definite proportion of gas to be drawn with liquid into the pump inlet and passed through the conduit in the form of voids or bubbles within the liquid.

2. An advertising display device, comprising a first liquid chamber containing a supply of liquid, a second liquid chamber which is open to atmospheric air and located adjacent said first chamber, a liquid circulating means having an inlet and an outlet, said inlet being located within said second chamber and spaced upwardly from the lower surface thereof, a transparent conduit connected to the outlet of said circulating means for receiving liquid from said circulating means and returning the same to said first chamber, and liquid flow control means connecting said first and second chambers for controlling the liquid level in said second chamber with respect to the inlet of the circulating means so that the inlet receives proportionate quantities of air and liquid from said second chamber, the former passing through said conduit in the form of spaced voids or bubbles within the liquid.

3. An advertising display device, comprising a liquid chamber in communication with a source of gaseous fluid, a liquid pump having an inlet and an outlet, the inlet of said pump extending into said chamber, a transparent conduit connected at one end to the outlet of said pump, a source of liquid, and valve means positioned between said source of liquid and said chamber for controlling the flow of liquid into said chamber at a rate of flow which is less than the maximum capacity of the pump whereby a portion of gaseous fluid is drawn in from the chamber with the liquid therein and is passed through the conduit in the form of voids or bubbles within the liquid.
